(57) **CLAIM**

The ornamental design for a standing base for canes, as shown and as also described.

DESCRIPTION

FIG. 1 is a top plan view of a standing base for canes showing the new design;

FIG. 2 is a bottom plan view thereof;

FIG. 3 is a right elevation view thereof;

FIG. 4 is a front elevation view thereof;

FIG. 5 is a left elevation view thereof;

FIG. 6 is a back elevation view thereof; and,

FIG. 7 is a front perspective view thereof.

The broken lines in the drawings are for the purpose of illustrating portions of the article that form no part of the claimed design.
